HAND OILER

Samuel O. Paul, Wellsburg, W. Va., assignor to
 Eagle Manufacturing Company, Wellsburg,
 W. Va., a corporation of West Virginia

Application July 8, 1936, Serial No. 89,625

8 Claims. (Cl. 221—51)

This invention is directed to an improvement in hand oilers of the type wherein, through the manipulation of handle-carried parts, the oil in the container is ejected through the spout at will.

Hand oilers of this type include a pump positioned within the container and a lever mounted on the handle to be operated to actuate the pump. The connection between the pump proper and spout extends through that portion of the handle ordinarily provided with means for closing the end of the container and this connection includes a pipe section of reduced diameter to increase the pressure and speed of flow, with means between this reduced pipe and spout so that the parts may be connected against leakage and to properly position and support the pump within the container.

Heretofore the connection between the pump pipe and spout has been constructed in two or more parts united by soldering and as the connection must afford a non-leaking passage for the oil and also provide a support for the pump parts, it has been found that under ordinary usage to which the oiler is subjected there has been a tendency to breakage or disconnection at the soldered joint which quickly renders the oiler as a whole inoperative for the purpose for which it was designed. Furthermore, the manufacture of the parts making up the connection and the independent and necessarily careful soldering of the joint requires several operations which have to be carefully carried out and at best tend to a rather limited life of maximum effectiveness of the oiler.

It is the primary object of the present invention to provide the connection between the pump proper including the pump pipe and the spout as an integral indivisible part which, when assembled, avoids the possibility of breakage or disconnection tending to leakage and inoperativeness and further insures the possibility of a rapid, uniform and proper assemblage of the parts to properly position the pump within a container and insure a removable connection of the spout which may be effectively sealed in a convenient, conventional manner.

A further object of the invention is the provision of means for removably supporting the pump-operating lever on the handle with a view to simplifying the connection and at the same time permitting the rocking operation of the handle necessary to pump operation.

The invention is illustrated in the accompanying drawing, in which:

Figure 1 is a view in side elevation, partly in section, showing the integral connection forming the subject-matter of the present invention in applied position and illustrating the pumping mechanism and handle in cooperative relation. 5

Figure 2 is a broken vertical section through the integral connection between the piston of the pumping mechanism and the spout forming the subject-matter of the present invention.

Figure 3 is a transverse section taken immediately above the enlarged portion of the handle to show the cooperation of the attachment and the opening in the enlarged portion of the handle to predetermine the position of the attachment. 10

Figure 4 is a broken perspective view showing the handle and lever, with the connecting means to permit relative movement of the lever, the parts being shown separated.

A pump assemblage of this character includes a pump involving a cylinder 1, a hollow plunger 2 operative therein, the bottom of the pump, which extends into the container, being formed in any conventional or desired manner with an inlet, non-outlet valve mechanism. 20 A handle 3 is provided which has a horizontal portion overlying the container and terminating at one end in an enlargement 4 to the under surface of which is secured in any appropriate manner a hollow threaded plug 5 which seats in and seals the opening in the upper end of the container. 25

As illustrated in the accompanying drawing, the pump part is made up of a cylinder 1, a hollow plunger 2 operative therein, the bottom of the pump, which extends into the container, being formed in any conventional or desired manner with an inlet, non-outlet valve mechanism. 30 A handle 3 is provided which has a horizontal portion overlying the container and terminating at one end in an enlargement 4 to the under surface of which is secured in any appropriate manner a hollow threaded plug 5 which seats in and seals the opening in the upper end of the container. 35

Removably though securely fixed to the plunger 2 is a feed pipe 6 of materially less diameter than that of the plunger to insure increased speed and pressure of the fluid delivered in the operation of the pump. This feed pipe is diametrically enlarged at an appropriate distance from the plunger to provide a locking section 7 which is exteriorly threaded. Above the locking section, the feed pipe is further diametrically enlarged 45 at 8 to provide between the sections 7 and 8 a limiting shoulder 9. Above the enlargement 8, the extended pipe section is further slightly increased in diameter to provide a positioning section 10 and above the positioning section, the 50

55

- pipe extension is further enlarged diametrically and exteriorly threaded to provide a spout-receiving section 11. The handle enlargement 4 and the bottom of the plug 5 are formed with vertically aligned openings 12 and 13 respectively through which the pipe extension is passed in the assemblage of the parts and the relation of the vertical dimensions of the parts is such that when in proper position the positioning section 10 fits within the opening 12 in the handle enlargement 4, allowing the spout-receiving section to rest squarely upon the upper surface of the handle enlargement and extend wholly above the same. The enlargement 8 of the handle section extends within the plug, terminating approximately in line with the bottom wall of the plug, while the threaded locking section 7 extends through and below the bottom wall of the plug.
- 20 In this type of oiler, in order to afford as complete a delivery as possible of the contents of the container, the pump proper is inclined to the vertical so as to terminate adjacent the wall of the container near the bottom and to thus position the pump proper, the feed pipe intermediate the plunger and locking section is slightly curved or bent to properly position the pump proper. As it is desirable and important that this positioning of the pump proper be maintained in the assembly, the feed pipe extension is formed to insure this position of the pump proper by providing the opening 12 with a flat portion 14 and in further flattening a corresponding portion of the positioning section 10 of the feed pipe extension, as at 15. Thus, the feed pipe extension can only be assembled with the handle in one position, and in this position the pump proper is arranged at a proper inclination within the container.
- 40 A lock nut 16 is loosely positioned on the feed pipe prior to the connection of the latter to the plunger, which lock nut is designed to engage the locking section 7 in the assemblage of the parts and bind or lock the feed pipe and feed pipe extension snugly between the bottom of the plug 5 and the top of the enlargement 4 of the handle, the lock nut engaging the bottom of the plug and the shoulder formed by the juncture of the spout-receiving section 11 and the positioning section bearing squarely upon the upper surface of the handle enlargement.
- Obviously, in the assemblage, the feed pipe and feed pipe extension are passed through the handle enlargement 4 and plug 5 from above, the lock nut loosely positioned upon the feed pipe proper and the plunger connected, and as in this assemblage the flat portion of the feed pipe extension 15 cooperates with the flat portion of the wall of opening 12 in the handle enlargement 4, the feed pipe and feed pipe extension are not only properly positioned to maintain the pump proper at the desired angle but held against rotative movement. A lock nut 16 is then threaded on the locking section 7 and tightened to rigidly unite the parts with the handle.
- It is to be particularly understood that the feed pipe and extension are a single integral part. There is no joint requiring soldering or other fixing and hence no possibility of leakage or breakage notwithstanding the continuous and hard usage of the oiler. There is an integral unit which extends from the plunger of the pump proper to the spout and hence liability of any leakage or any breakage is entirely and wholly obviated. This feed pipe unit, so-called, is of course independently constructed as a unit by proper machining in the usual manner and when completed affords not only a completely effective non-leaking, uninterrupted connection between the pump proper and the spout but provides a connection which presents the maximum protection against breakage or leakage and which, through its unit construction, is readily and conveniently assembled and may be as conveniently removed in disassembling the parts.
- The integral feed pipe extension is of course formed with a longitudinal bore 17 for the passage of oil, which bore, within the transverse area of the enlargement 8, is diametrically increased at 18 throughout the remaining length upwardly of 15 the feed pipe extension. The juncture of the respective diameters of the bore are formed to provide a valve seat 19 on which is positioned a valve, preferably a ball valve 20. The upper end of the bore enlargement 17 is further increased in 20 diameter at the upper end of the spout-receiving section 11, providing a narrow shoulder 21 to receive the upper out-turned ends 22 of a U-form cage 23, the cross bar 24 of which overlies the valve and prevents undue upward movement of 25 the same during operation or in any desired position of the oiler. The cage is of course readily removable for access to the valve and seat when desired.
- The cylinder 1 of the valve proper has secured 30 to the outer surface thereof near the outer end a bifurcated hook 25, and a rod 26 extends through appropriate openings in the enlargement 4 of the handle and the bottom of the plug 5 and is reduced in thickness at its lower end, as at 27, to fit 35 in the bifurcation in the hook, with the terminal 28 of the rod fitting in the bend of the hook to removably connect the rod and cylinder of the pump.
- The handle proper includes an integral depending portion 29 which extends down free of and lengthwise the container, the lower end of the depending portion being preferably upturned to afford a convenient handle grip. An operating lever 30 is mounted for rocking motion upon the 45 horizontal portion of the handle, with the free or operative portion of the lever positioned for free manipulation by a finger of the hand gripping the handle grip. The inner end of the lever is formed with an elongated opening 31 through 50 which the upper end of the rod 26 extends, the rod being headed to permit elevation of the rod and thereby upward movement of the cylinder of the pump proper against the usual return spring on depression of the outer end of the lever.
- The invention contemplates a novel method of supporting the lever to provide for the rocking movement of the latter, and to this end the material of the horizontal portion of the handle is cut out in the form of a T and the material thus cut 55 out is bent upwardly to provide a projection having an upright portion 32 extending upwardly at right angles to the horizontal portion of the handle and an upper terminal extending in both directions beyond the upright portion to provide end projections 33. The operating lever 30 is depressed at a point intermediate its length to provide a rocking or fulcrum point which bears upon the horizontal portion of the handle and this depressed portion of the lever is cut away, as at 34, 60 in the form of a slot having a length corresponding to the length of the upper end portion of the projection 33, the central portion of the slot 34 being enlarged on more or less curved lines, as at 65 35, to permit a rotative movement of the neck 75.

or shank of the upstanding portion 32 of the handle.

The lever is assembled by passing the upper end portion 33 of the upstanding portion 32 through the slot 34, the lever in this position being at right angles to the handle portion. The lever is then turned into alignment with the handle portion, so that the enlarged upper end 33 of the upstanding portion 32 of the handle projection extends transverse the slot, with the lever aligned with the handle. The rod 26 is then passed through the opening 31 of the lever, the aligned openings in the handle enlargement 4 and the bottom of the plug 5, and engaged with the bifurcated hook 25 of the pump cylinder.

The spout 36 is of course removably connected to the spout-receiving section 11, preferably by a coupling 37, suitable gaskets maintaining a tight connection.

20 The unitary formation of the feed pipe and feed pipe extension to insure strength, prevent leakage and avoid the necessity of soldering or other connection tending to leakage or breakage is a practical and commercial advantage in oilers 25 of this type as it not only simplifies the assemblage but it materially increases the strength and life of the oiler as a whole.

What is claimed to be new is:

1. A hand oiler of the type including a container, 30 a removable handle, a pumping mechanism within the container, and a spout, comprising an integral element passing through the handle, connected at one end to the pumping mechanism and at the opposite end to the spout, said element having a valve controlled bore leading therethrough to establish communication between the pumping mechanism and the spout, and means for removably fixing the element with respect to the handle.

40 2. A hand oiler of the type including a container, a removable handle, a pumping mechanism within the container, and a spout, comprising an integral element passing through the handle, connected at one end to the pumping mechanism and at the opposite end to the spout, said element having a valve controlled bore leading therethrough to establish communication between the pumping mechanism and the spout, and means for removably fixing the element with respect to the handle,

45 said means including a shoulder overlying the handle adjacent the spout end of the element, and a nut having threaded connection with the element below the handle for removably securing the element in place.

50 3. A hand oiler of the type including a container, a removable handle, a pumping mechanism within the container, and a spout, comprising an integral element passing through the handle, connected at one end to the pumping mechanism and at the opposite end to the spout, said element having a valve controlled bore leading therethrough to establish communication between the pumping mechanism and the spout, and means for removably fixing the element with respect to the handle, said element including a pipe section removably connected to an element of the pumping mechanism and a relatively en-

larged section overlying the handle when the element is in place and exteriorly threaded to receive the spout connection.

4. A hand oiler of the type including a container, a removable handle, a pumping mechanism within the container, and a spout, comprising an integral element passing through the handle, connected at one end to the pumping mechanism and at the opposite end to the spout, said element having a valve controlled bore leading therethrough to establish communication between the pumping mechanism and the spout, and means for removably fixing the element with respect to the handle, said element including a pipe section removably connected to an element of the pumping mechanism and curved longitudinally to properly position the pumping mechanism within the container, and cooperating means on the element and handle to predetermine the position of the element with respect to the handle to arrange the pipe section to properly position the pumping mechanism.

5. A construction as defined in claim 4, wherein in the positioning means of the element includes cooperating flattened portions of the element and the wall of the opening in the cap through which the element projects.

6. A construction as defined in claim 4, wherein in the bore of the element is formed to provide a valve seat, a valve cooperating with said seat to prevent down-flow through the element, and a cage removably supported in the element for holding the valve against complete upward freedom of movement.

35 7. A hand oiler including a container, a pumping mechanism therein, a handle, a lever supported for rocking movement on the handle, a connection between the lever and pumping mechanism to operate the latter in the movement of the lever, and means for supporting the lever on the handle for rotating movement, said means including a T-form section cut from the handle and turned upwardly, and a slot in the handle formed to cooperate with the T-form section in an inoperative position of the handle to permit application of the handle, the relation of the slot and handle holding the handle against separation from the T-form section when the handle is in operative position.

40 8. A connector for use in hand oilers of the type including a container, a removable cap therefor, a pumping mechanism within the container, a spout, and means associated with the cap for operating the pumping mechanism, said connector comprising an integral element passing through the cap and forming an extension of one part of the pumping mechanism, said element being formed with a longitudinal bore constituting a fluid outlet from the pump, means associated with the element alone for clamping the element in fixed relation to the cap, said means being operable to readily free the element from the cap at will, said element when in fixed relation to the cap extending beyond the cap and being formed in such extension to removably receive the spout.
